UNITED STATES PATENT OFFICE.

JAMES FORSHAW PRICE, OF BOSTON, MASSACHUSETTS.

DESIGN FOR A CHARM.

SPECIFICATION forming part of Design No. 29,166, dated August 9, 1898.

Application filed June 16, 1898. Serial No. 683,620. Term of patent 3½ years.

To all whom it may concern:

Be it known that I, JAMES FORSHAW PRICE, a citizen of the United States, residing at South Boston, in the county of Suffolk and

5 State of Massachusetts, have invented and produced a new and original Design for a Charm, of which the following is a specification, reference being had to the accompanying drawings, forming a part thereof, in which—
10 Figure 1 is a front elevation of a charm embodying the features of my design, and Fig. 2 is a transverse section taken practically on the line 2 2 of Fig. 1.

15 The leading feature of the design consists in the marginal configuration A, representing

a horseshoe, a panel B within the representation of the horseshoe, said panel appearing transparent, and the decoration for the panel representing a spray C of shamrock.

Another feature of the invention consists of 20 a bar D, connecting the heel portions of the shoe.

I claim—

The design for the charm herein shown and described.

JAMES FORSHAW PRICE.
